UNITED STATES PATENT OFFICE.

EDWARD P. COLE, OF CHICAGO, ILLINOIS, ASSIGNOR TO COLE MANUFACTURING COMPANY, OF CHICAGO, ILLINOIS, A CORPORATION.

DESIGN FOR A WARMING-OVEN FOR A RANGE.

55,747.

Specification for Design.

Patented July 13, 1920.

Application filed December 22, 1919. Serial No. 346,808. Term of patent 14 years.

To all whom it may concern:

Be it known that I, EDWARD P. COLE, a citizen of the United States, and a resident of Chicago, county of Cook, and State of Illinois, have invented a new, original, and ornamental Design for a Warming-Oven for a Range, of which the following is a specification, reference being had to the accompanying drawing, forming a part hereof.

In the drawing, Figure 1 is a front elevation and Fig. 2 is a side elevation of a warming oven for a range showing my new design.

The essential features of my design con-

sist in the general outline of the elevated warming oven and its support and the bevel-edged paneling of the door, substantially as shown in the drawing. The elevated warming oven is adapted to be mounted upon a range body.

I claim:

The ornamental design for a warming oven for a range, substantially as shown and described.

EDWARD P. COLE.
